UNITED STATES PATENT OFFICE.

JAMES B. McCUTCHEON, OF BAKERSFIELD, CALIFORNIA.

BANK-PROTECTIVE DEVICE.

Application filed May 24, 1924. Serial No. 715,512.

This invention relates to safe guarding devices which are adapted to retard egress through a doorway.

The general object of the invention is to provide an improved exitway obstructing device.

One of the specific objects of the invention is to provide an exit closing device wherein a plurality of movable members are arranged and concealed adjacent an exit and are adapted to be moved to operative position to close the exit when desired.

Another object of the invention is to provide a doorway including a hinged door, with a plurality of pivoted members arranged on opposite sides of the doorway and connected to operating members in such a way that the operating members may be actuated to move the exit closing members to operative position to close the exit whether the door is open or closed.

Other objects of the invention will be apparent from the following description taken in connection with the accompanying drawings wherein Fig. 1 is an elevation of a doorway showing my invention applied thereto; Fig. 2 is a central section through a doorway showing my invention in elevation; Fig. 3 is a wiring diagram; Fig. 4 is a section taken on line 4—4, Fig. 1; Fig. 5 is an end view of the slot in which the pivoted arms are secured; Fig. 6 is a section showing one of the pivoted arms in elevation; Fig. 7 is a view similar to Fig. 6 showing the other arms; Fig. 8 is a fragmentary elevation showing a part of an arm and a limit switch; Fig. 9 is a section taken on line 9—9, Fig. 8 showing the limit switch and Fig. 10 is an enlarged detail showing the ratchet.

Referring to the drawing by reference characters, I have shown a wall at 10. This wall is shown as provided with an opening 11 therethrough. The opening I have shown as a doorway having a casing 12 thereabouts, but it will be understood that this opening is merely typical and that my invention may be used in connection with a window or other exitways if desired.

The casing is indicated as provided with a door 14 which is hinged to the casing as

at 15. The casing is shown as provided with a groove 16 along each opposed vertical side thereof.

Within the grooves 16 I arrange a plurality of pivoted arms 17, 18 and 19. An operating member 20 serves to move the arms. The arms are each pivoted on members 21 in the grooves 16. Intermediate their length and at their inner ends the arms are pivoted as at 21 to an operating member 23. The operating member 23 is preferably a rectangular strip of material which extends substantially the full length of the casing. The arms 17 are pivoted to the operating member on the side thereof which is closest to the door 14 as shown in Fig. 4. The intermediate arms 18 are shown as provided with a yoke 22 at the inner end which straddles the operating member 23, while the arm 19 engages the side of the operating member 23 which is furthest removed from the door 14. The arms and this operating member are preferably of metal.

In one position the arms 17, 18, and 19 which are arranged in regular order so that they will not interfere with each other are adapted to be disposed substantially horizontally as shown in Fig. 1 so that they will obstruct the opening 11. The upper arms, as will be noted, in Fig. 1, are made shorter than the other arms since this construction is necessary in order that the arms will fit within the grooves 16. The exposed ends of the arms may be pointed or sharpened if desired.

Each arm is provided with a slot 25 adjacent the pivot 21 in which the pivot fits, so that the operating member 23 which is held against movement in any but a vertical direction, can move without binding.

When the arms are arranged substantially vertical within the groove 16 each arm will rest with its upper portion adjacent the pivot 21 of the arm next above it so that the arms will assume a slightly inclined position as shown in Fig. 8. In order to move the operating members 23 one of which is arranged in each side of the casing, I show these arms as provided with racks 30 which are adapted to engage pinions 31 mounted

on a shaft 32 which is adapted to be driven by a pinion 33 arranged upon the shaft 34 of an electric motor 35.

In order to prevent downward movement 5 of the operating member 23 I show the shaft 32 as provided with a ratchet 37 which is adapted to be engaged by a pivoted pawl 38 which in turn engages a stop 39 on a support 40. A spring 41 normally engages the 10 pawl 38 to hold it in the position shown in Fig. 10, while the operating member 42 enables the pawl 38 to be raised.

The motor 35 is shown in Fig. 3 as having one terminal 44 thereof connected by means 15 of a lead 45 with a battery 46. A plurality of switches 47 are arranged along the lead 45 and the construction is such that any one of these switches 47 may serve to close the circuit to the battery. The terminal 48 of the motor is shown as connected by a lead 49 with the other side of the battery 46. The lead 49 includes a limit switch 50 shown in detail in Fig. 9 also a manual switch 51. The operation is such that when any one of 20 the switches 47 is closed the circuit will be complete from the battery through the switches 51 and 50, lead 49, terminal 48, the motor 35, the terminal 44, lead 45, a switch 47 and back to the battery 46.

25 The switch 50 which is shown in detail in Figs. 8 and 9 includes a pair of spaced terminals 50' mounted in the rear of the groove 16 while the circuit closure 51 for this switch is arranged on the operating member 23. The construction is such that when the operating member moves upwardly to the position shown in Fig. 8 so that the arms 17, 18 and 19 are horizontal then the circuit closure 51 will be disposed above the terminals 50' of the switch 50 so that the circuit will be broken. The arms 17, 18 and 19 will however remain horizontal until the pawl and ratchet 37, 38 is released.

30 The device is provided with an audible signal which may be a bell 60 which is connected by a lead 61 with the lead 45 on one side and on the other side is connected by the lead 62 with the battery 46. From the construction described and by referring 35 to the diagram shown in Fig. 3 it will be seen that when a switch 47 is closed the bell 60 will operate and that when the switch 50 is opened the bell 60 will continue to sound, so that after the arms 17, 18, and 19 have moved to position to obstruct the passageway the alarm bell will continue its operation.

35 The motor 35 is preferably a reversible one and the reverse operation is shown as effected through a lead 63 to one side of the battery and a lead 64 on the other side of the battery. The switch 51 is adapted to close the circuit to reverse the motor. This switch is so constructed that when it closes 40 the circuit through the lead 64 it opens it

through the lead 49 as will be apparent by referring to Fig. 3.

From the foregoing description it will be apparent that when one of the switches 47 is closed that the arms 17, 18, and 19 70 will move to horizontal position and that the bell 60 will ring and that the bell will continue ringing until the switch 47 is again operated.

Having thus described my invention, I 75 claim:

1. In an exit closing device, a doorway, a recess in opposite sides of said doorway, a plurality of arms pivoted in each recess, said arms being adapted to be disposed vertically entirely within the recesses so that said doorway is unobstructed, a vertically movable operating rod in each recess, said rods being pivotally attached to the ends of said arms and movable to cause said arms to 80 obstruct the exitway, a rack on said rods, move said pinions and mechanically operated means for locking the pinions against movement in one direction.

2. In an exit closing device, a doorway 90 having a casing therein including top and side members, a plurality of spaced arms pivoted on horizontal pivots to said side members, said arms being adapted to be normally disposed vertically so that said doorway is unobstructed, means for operating said arms to cause them to move to horizontal position to obstruct the exitway, said operating means being disposed in 95 said recess, certain of said upper arms being shorter than the lower arms, and means for locking the arms in horizontal position.

3. In an exit closing device, a doorway, a recess in opposite sides of said doorway, 105 a plurality of arms pivoted in each recess, said arms being adapted to be disposed in the recesses so that said doorway is unobstructed, and means for operating said arms to cause them to obstruct the exitway, said means comprising operating members, a rack on each member, a shaft adjacent 110 said doorway, said shaft having pinions thereon meshing with said racks and means for operating said shaft, said means comprising a motor, a circuit to said motor and means for closing the circuit to the 115 motor to operate the same, means to limit the movement of said arms, said last mentioned means operating to open said circuit.

4. In an exit closing device, a doorway, a recess in opposite sides of said doorway, a plurality of arms pivoted in each recess, said arms being adapted to be disposed vertically in the recess so that said doorway is unobstructed and means for simultaneously operating said arms to cause them to obstruct the exitway, said means comprising vertical members to which said arms are 125 pivoted, a rack on each member, a shaft ad- 130

jacent said exitway said shaft having pinions thereon meshing with said rack, and means for operating said shaft, said means comprising a motor, a circuit to said motor and means for closing the circuit to the motor to operate the same, other means for causing said motor to reverse, means to

limit the movement of said arms, said last mentioned means operating to open said circuit.

10

In testimony whereof, I hereunto affix my signature.

JAMES B. McCUTCHEN.
